UNITED STATES PATENT OFFICE.

JAMES DEENIHAN, OF REDONDO BEACH, CALIFORNIA.

COMBINED DOOR HOLDER AND CHECK DEVICE.

Application filed December 19, 1925. Serial No. 76,430.

This invention has relation to a combined door holder and check of the suction cup type.

- A main object is to provide a suction holder for swinging objects, such as doors, windows, and the like that will automatically engage the same when such objects are moved from one position to another to hold the same from further movement.
- 10 A further object is to provide a suction holder for doors and like structures that will also act as a cushioning device, that will not mar the surfaces of objects engaged, and which is provided with means whereby the
- 15 suction may be readily broken to release the object held thereby when it is desired to move or swing the object into a closed position.

Cushioning devices, such as rubber tipped stops, are now universally employed in building structures to limit the movement of door and casement when swung to an open position, in order that the surfaces of the doors and adjacent framework will not be marred or disfigured. While such stops efficiently perform their intended functions, yet no provision as far as I am aware has been made to automatically cushion the door when opened to its fullest extent and at the same time securely hold the same against accidental closure, except mechanical metal devices such as hooks, catches, and like devices.

By means of the present invention the door or other object is not only cushioned at the end of the opening movement but is automatically engaged and securely held in its opened position until manually released.

One form of my invention is illustrated in the accompanying drawings, in which:

Fig. 1 shows an application of the device in connection with a swinging door.

Fig. 2 is a perspective view of the device.

Fig. 3 is a sectional view of the device engaged by a door.

Fig. 4 is a similar view showing another form of suction cup support.

Fig. 5 is a side view of the device showing the automatic cup releasing means.

50 Fig. 6 is a similar view with the cup in section, showing a modified form of cup releasing means.

Figs. 7-8 are front face views of suction cups showing other modified cup releasing means.

In an embodiment of the present invention, especially the forms as shown in Figs. 1 to 4 inclusive, 5 designates a holder support formed of a single piece of strap iron, its ends 6, 7, being bent in opposite directions 60 to its body portion to form means of attachment and a support for the vacuum cup holder respectively. End 6 is provided with an aperture for the passage of a screw therethrough when the support is attached to the base board of a building partition 8, and the opposite end 7 is also apertured for the passage of a bolt 9 for securing the cup shaped rubber suction holder 10 thereto. The thickened base 11 of the catch is preferably 65 countersunk as at 12 to chamber the bolt head, and its outer circular wall tapers outwardly towards its periphery in order to render the same flexible and insure perfect suction when the door or other object to be held 70 is brought thereagainst.

In Figs. 4 and 5 the holder support is shown as formed of a wooden cylinder 13, provided with a bore 14 therethrough for the passage of the securing screw 15, which 80 serves to hold the suction cup catch 10, and the cylinder 13 to the support.

When a door or other swinging object is brought against the cup holder, as shown in Figs. 3 and 4, the air therein will be expelled therefrom to form a partial vacuum to firmly hold the door in engagement therewith. I have found in actual practice that the suction of the cup is so great that it requires considerable force to disengage the door from the cup when it is desired to close the same, and in order to render it comparatively easy of detachment I have provided a means for destroying the partial vacuum formed in the cup on a slight pull on the door. In Figs. 2 and 6, the cup 10 is provided with a rib 16 on its outer surface extending from its circular edge to its thickened base. By means of this rib when a pull is exerted on the door, the edge of the cup adjacent the portion stiffened by the rib will quickly disengage and thus destroy the vacuum in the cup and insure a quick release. In Fig. 5 instead of a rib, a cord 17 is secured to a lug 18 formed on the outer surface of the cup near its circular edge, its free end being secured to the wooden cylinder 13. In this form it will be apparent that as soon as a door which is held by the holder cup is pulled away from the same the

cord 17 will hold the edge of the cup at its point of attachment to quickly disengage the said edge of the cup from engagement with the door and thus destroy the suction 5 of the cup.

In Figs. 7 and 8 still other modified forms of cup releasing means are shown, the form shown in Fig. 7 consisting of a small air bleed opening 19 formed adjacent the circular edge of the cup. It will be apparent that when a door is pushed into engagement with the cup that the circular flexible edge will be spread to cover the opening 19 and thus maintain a perfect cup suction. As 10 soon as a pull is exerted on the door to close the same the circular edge will stretch sufficiently to permit of an entrance of air through the opening 19 to destroy the partial vacuum in the cup to quickly release the 20 door from engagement therewith. The form shown in Fig. 8 is substantially the same as in the preceding figure except instead of the opening 19 a notch 20 is formed in the circular edge of the cup.

25 While I have shown the suction device secured to a building partition in the path of a swinging door, yet it will be perfectly obvious that the device may be secured to the door itself with equally satisfactory results.

From the above description it will be apparent that I have provided a simple device that will effectively engage and hold a door against an accidental closing movement when 35 the same has been opened, and will also act

as a cushioning stop to prevent injury to the finished surface of the door.

What I claim is:

1. A suction door holder comprising a cup shaped member formed of a resilient material adapted for securement to a support and disposed in the path of a swinging door, said suction member adapted to engage and hold the door against movement by the suction of the cup shaped member when the 45 same is brought thereagainst.

2. A suction door holder comprising a resilient cup shaped suction member and means for securing the same to a support, said suction member adapted to engage and hold a door against movement when brought in contact therewith, and means associated with said suction member for destroying the suction therein when a pull is exerted on the door to close the same. 50

3. A suction door holder comprising a supporting member adapted for attachment to a stationary support, and a resilient cup shaped suction member secured to said supporting member adapted to engage and hold a door by suction when swung thereagainst, said cup shaped member having a bleeder opening formed therein, whereby to quickly destroy the suction in the cup when a pull is exerted on the door to disengage the same 55 from the cup.

In witness that I claim the foregoing I have hereunto subscribed my name this 8th day of December, 1925.

JAMES DEENIHAN.
